(57) **CLAIM**

The ornamental design for a remote ready temperature gauge, as shown and described.

DESCRIPTION

FIG. 1 is a right side isometric view of a remote ready temperature gauge showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a top plan view thereof in accordance with a further embodiment of the invention.

The dashed lines shown on the drawings represent unclaimed portions of the design and form no part thereof.
